UNITED STATES PATENT OFFICE

CHARLES B. DRAKE, OF NORFOLK, VIRGINIA

ADVERTISING CLOCK

Application filed April 9, 1932. Serial No. 604,331.

My invention relates to new and useful improvements in clocks and while I have illustrated and will describe the same as being electrically operated it will be understood that it might be operated by any other suitable means.

The principal object of the invention resides in the provision of means for displaying advertising matter, this means including a disc adapted to be secured to and operable with the second hand shaft of the clock, the advertising matter being so arranged upon the disc that it may be continuously read as the disc is rotated.

15 A further object of the invention consists in the provision of a shield having a sight opening through which the advertising matter on a portion of the disc may be read, said shield being supported by and operable relative to the second hand shaft to which the disc containing the advertising matter is secured.

25 Another object of the invention resides in the provision of a novel form of hub unit or member for securing the disc containing the advertising matter to the second hand shaft, said unit or member also being provided with bearing portions adapted for mounting the shield relative to the disc.

30 Still another object of the invention consists in forming the shield so that the same will be balanced to position the sight opening therein, at all times, at the bottom thereof, it being understood that the advertising matter may be read through the sight opening as the disc containing the same is rotated.

With the above and other objects in view, which will appear as the description proceeds, my invention consists in the novel details of construction, and arrangement of parts, described in the following specification and illustrated in the accompanying drawing, and while I have illustrated and described the preferred embodiments of the invention, as they now appear to me, it will be understood that such changes may be made as will fall within the scope of the 50 appended claims.

In the drawing:

Fig. 1 is a front face view of the clock.

Fig. 2 is a horizontal section on the line 2—2 of Fig. 1 looking in the direction of the arrows.

Fig. 3 is a vertical section on the line 3—3 of Fig. 1 looking in the direction of the arrows.

Fig. 4 is a fragmental detail showing a section on the line 4—4 of Fig. 3 looking in the direction of the arrows; and

Fig. 5 is a rear face view of the disc containing the advertising matter and the shield positioned relative thereto.

In the drawing 1 indicates a housing or casing having the glass front plate 2 held in position by the frame 3 which surrounds and overlies the edges thereof, as shown more particularly in Fig. 2 of the drawing. Positioned behind the front plate is a plate 4 bearing the usual clock numerals. Supported interiorly of the housing or casing, by the bracket 5 or other suitable supporting means is a motor 6, shown as a synchronous electric motor although any other desired suitable motor may be used. Operated by the motor are the usual hour and minute hands shown at 7 and 8 respectively and at 9 I have shown a second hand shaft to which a second hand is usually connected and by which it is usually operated. In my present construction I do away with said second hand and instead secure to the shaft, by means of a hub unit or member, a disc or plate 10 which bears the advertising matter arranged as shown more particularly in Fig. 1 of the drawing. The outer end of the shaft 9 is tapered as shown at 11 and this tapered end is received in a tapered opening formed in the hub unit or member indicated generally at 12, this hub unit or member being provided on its inner face with a reduced extension 13 and on its outer face with a reduced extension 14, these extensions being used as bearings for supporting the shield to be later described.

Intermediate the reduced extensions 13 and 14 the hub unit or member is provided with the outwardly directed flange 15 against which the inner face of the disc 10 is adapted to rest as shown more particularly in Fig. 4

of the drawing, the disc being held in position by means of the nut 16 received on the threaded portion 17 of the unit or member 12. In other words the disc or plate 10 is clamped between the flange 15 and the inner face of the nut 16. It will be seen that as the second hand revolves the disc or plate 10 will likewise be revolved or rotated in the direction indicated by the arrows in Fig. 1

10 of the drawing.

In order to obscure a portion of the advertising matter on the disc or plate 10 I provide a shield which is suspended or mounted on the hub unit or member and while the shield is freely rotatable relative to said hub unit or member it is counter-balanced to be held in the desired position. The shield includes a plate 18 provided with the sight opening 19 and having its outer edge turned to provide a flange 20. Connected to the flange 20 and spaced from the rear face of the disc or plate 18 is a plate or strip 21 of the shape shown more particularly in Fig. 5 of the drawing with one end of greater width than the other so that the bottom of the strip or plate will be of greater weight than the top portion thereof. This strip or plate 21 acts as a counter-balancing weight to normally hold the shield in the position shown more particularly in Figs. 1, 3 and 5 of the drawing with the sight opening 19 exposing the lower half of the disc or plate 10. The strip or plate 21 is provided at its narrow end with the prong 22 and at its wider end with the prongs 23, these prongs 22 and 23 extending through openings formed in the flange 20 as shown more particularly in Figs. 3 and 5 of the drawing. The extension 14 of the hub unit or member 12 extends through an opening formed in the plate 18 of the shield whereas the extension 13 extends through an opening formed in the counter-balancing plate 21. Thus the shield is mounted on or suspended from the hub unit and while it is readily rotatable relative to said unit it is held in proper position, as previously described, by the counter-balancing strip or plate 21.

At 24 I have shown a feed wire for furnishing current to the motor 6.

From the above detailed description it is thought that the construction and operation will be clearly understood. The advertising matter carried by the disc or plate 10 may be continuously read, as the disc or plate is rotated, through the sight opening 19 and the shield obscures the advertising matter on the upper portion of the plate or disc. The counter-balancing plate or strip 21 holds the shield, at all times, with the sight opening at the bottom and it will be understood that although the second hand shaft 9 and the disc or plate 10 carried thereby will be rotated nevertheless the shield will not rotate, it being freely mounted on the hub unit as previously described.

Having fully described my invention what I claim as new and desire to secure by Letters Patent is:—

1. A clock of the character described including a shaft and means for operating the same, a display member connected to the shaft, and a shield supported by the shaft, said shield having an opening through which matter on the display member may be observed. 70

2. A clock of the character described including a shaft and operating means therefor, a display member connected to the shaft, and a counter-balanced shield supported by the shaft, said shield having an opening normally positioned to permit observation of the display matter on a portion of the display member. 75

15 3. A clock of the character described including a shaft and operating means therefor, a display member connected to and operable with the shaft, and a shield supported by the shaft, said shield being freely rotatable relative to the shaft and provided with an opening through which a portion of the display matter on the display member may be observed. 80

20 4. A clock of the character described including a shaft and operating means therefor, a disc containing advertising matter, means for detachably connecting the disc to the shaft, 95 and a shield mounted on the shaft, said shield being formed and adapted to obscure a portion of the advertising matter on the disc.

25 5. A clock of the character described including a shaft and operating means therefor, a display member carried by the shaft, and a shield supported by the shaft relative to the display member, said shield being formed and adapted to obscure a portion of the display matter on the display member. 100

30 6. A clock of the character described including a shaft and operating means therefor, a hub member carried by the shaft, a disc secured to the hub member for containing advertising matter, and a shield supported by the hub member, said shield being formed and adapted to obscure a portion of the advertising matter on the disc. 105

35 7. A clock of the character described including a shaft and operating means therefor, a hub member carried by the shaft, means for securing a disc containing advertising matter to the hub member, and a shield supported by the hub member and freely rotatable relative thereto, said shield being formed 110 and adapted to obscure a portion of the advertising matter on the disc. 115

40 8. A clock of the character described including a shaft and operating means therefor, a hub member carried by the shaft and provided with reduced extensions, a disc containing advertising matter, means for securing the disc to the hub member, and a shield mounted on the reduced extensions of the hub member, said shield being formed and adapted 125

120

130

to obscure a portion of the advertising matter on the disc.

9. A clock of the character described including a shaft and operating means therefor, a hub member detachably connected to the shaft and provided with reduced extensions, a disc containing advertising matter, means for detachably connecting the disc to the hub member, and a counter-balanced shield 10 mounted on the reduced extensions of the hub member, said shield being formed and adapted for obscuring a portion of the advertising matter on the disc but permitting view of the advertising matter on the other portion of the 15 disc.

10. A clock of the character described including a shaft and operating means therefor, a display member connected to and operable with the shaft, and a shield mounted 20 on the shaft and provided with an opening through which matter on the display member may be read, said shield including a flange and a plate connected thereto, said plate being of greater width at one end than at the other to 25 counter-balance the shield on the shaft.

In testimony whereof I hereunto affix my signature.

CHARLES B. DRAKE.
